(57) **CLAIM**

The ornamental design for a fish retrieval apparatus, as shown and described.

DESCRIPTION

FIG. 1 is a perspective view of the fish retrieval apparatus showing my new design according to a first embodiment;

FIG. 2 is a front elevational view of the first embodiment, the rear elevational view of the first embodiment being the same;

FIG. 3 is a bottom plan view of the first embodiment;

FIG. 4 is a top plan view of the first embodiment;

FIG. 5 is a left side elevational view of the first embodiment, the right side elevational view of the first embodiment being the same;

FIG. 6 is a perspective view of the fish retrieval apparatus showing my new design according to a second embodiment;

FIG. 7 is a front elevational view of the second embodiment, the rear elevational view of the second embodiment being a mirror image;

FIG. 8 is a bottom plan view of the second embodiment;

FIG. 9 is a top plan view of the second embodiment;

FIG. 10 is a left side elevational view of the second embodiment; and,

FIG. 11 is a right side elevational view of the second embodiment.

Any broken line illustration of environmental structure in the drawings is not part of the design sought to be patented.
